UNITED STATES PATENT OFFICE.

GEORGE S. BARTOLD, OF ROCHESTER, NEW YORK, ASSIGNOR TO LORSCHEIDER-SCHANG CO., INC., OF ROCHESTER, NEW YORK, A CORPORATION OF NEW YORK.

PAPER BOX.

Application filed April 10, 1922. Serial No. 550,983.

To all whom it may concern:

Be it known that I, GEORGE S. BARTOLD, of Rochester, in the county of Monroe and State of New York, have invented certain new and useful Improvements in Paper Boxes; and I do hereby declare the following to be a full, clear, and exact description of the same, reference being had to the accompanying drawings, forming a part of

10 this specification, and to the reference numerals marked thereon.

My present invention relates to special receptacles and more particularly to paper boxes of the general type used for face powder and like goods, and it has for its object to provide a simple, strong and durable box of attractive appearance so reinforced with metal as to greatly increase its wearing qualities and at the same time assist in its 15 ornamentation. To these and other ends the invention consists in certain improvements and combinations of parts, all as will be hereinafter more fully described, the novel features being pointed out in the claims at 20 the end of the specification.

In the drawings:

Figure 1 is a side view of a powder box constructed in accordance with and illustrating one embodiment of my invention;

30 Figure 2 is a bottom view thereof;

Figure 3 is an enlarged central section, and

Figure 4 is an enlarged fragmentary section of a corner of the box as shown in 35 Figure 3.

Similar reference numerals throughout the several views indicate the same parts.

In general form the box is of a familiar design with a deeply flanged cover having a 40 rounded top and a cylindrical bottom fitted with an inner collar over which the cover engages so that the dividing line of the box appears to be at about the center. In the practice of my invention I construct the 45 walls of the cover portion A and the body portion B of laminated material in practically the same manner, to wit: a cylindrical paper side wall 1 forms a lining for and is surrounded by a thin band or hoop 2 of 50 bronze or similar ornamental metal on the outer face of which is secured another paper lamination 3 that is preferably pasted to closely adhere and constitute an ornamental covering for the exterior. In the case of 55 the body of the box the lower edge of this

metallic lamination 2 extends beyond the paper layers at 4 to be wholly exposed and provide a gilt band at the lower edge or corner of the box for purposes of ornamentation. This portion 4 is also rolled inwardly 60 to form a bead as shown that provides a ledge upon which is seated a paper disk 5 constituting one end of the box, in this case the bottom. The margin of this bottom piece preferably abuts the metallic band 2 65 and lies beneath the paper lamination 1 as shown. The effect of this is not only to ornament the box, but it raises the paper bottom 5 so that it does not come in contact with the surface upon which the box is 70 placed, and in case such surface is damp or liquid has been spilled thereon, only the metal bead 4 becomes wet, and this being of course impervious to moisture, the box does not in any degree disintegrate as a result in the manner of boxes made wholly of 75 paper.

As before stated and as the reference numerals show the cover portion A is constructed in substantially the same manner at 80 least as far as the side walls are concerned. The lower edge 4^a of the metal band 2 may be exposed or not at the separating line of the parts, it being exposed in the present embodiment as shown at 4^a and arranged to 85 abut a small doubled edging strip 6 that straddles the top edge of the side wall of the body portion as shown in Figure 3. The upper or end edge projects and is beaded at 4^b, but it is usually desired in such 90 boxes to make a rounded or upwardly bulged top to give the appearance of the familiar padded top, so while I provide a flat disk 5^a for the upper end wall arranged in substantially the same manner as the bottom 95 5 I interposed between it and its seat on the bead 4^b a second outer and dished paper top 7 so that the edges of both of these parts of a double end wall are held between the bead and the edge of the paper lamination 1. 100 This outer wall or top has the same ornamental facing or covering 3^a as the side walls.

On the interior of the body portion B is the usual collar 8 constituting in effect an 105 inner container for the powder contents 9, the bottom of which is however the bottom 5 of the box. A frangible paper covering 10 is stretched across the top of the collar and pasted at the sides under a thin paper band 110

11. The collar projects above the rim of the side wall proper of the body and the cover portion fits over it as shown, and as usual in boxes of this kind.
- 5 I am aware that boxes of substantially this type and general appearance have been made before wholly of paper, but by combining paper and metal in the manner I have described, the box is given a smoother and 10 more regular appearance; the parts have greater body and stiffness; the gilt ornamentation provided by the exposed metal rim has a better finish and is more lasting; it is easy to manufacture and assemble with 15 an accurate fit, and it stands wear much better than a box that is all paper, particularly the beads 4 and 4^b which as before stated, are not damaged by moisture and save the box from disintegration at the corners 20 which readily occurs with a paper box having a rolled edge of any kind.

I claim as my invention:

1. A paper box having incorporated in its side walls a thin inner sheet of metal, an 25 end edge of which projects beyond the paper of the side wall and also beyond the edge of the adjoining end wall to constitute an ornamental band.

2. A paper box having incorporated in its

side walls a thin inner sheet of metal, an 30 end edge of which projects beyond the paper of the side wall and also beyond the edge of the adjoining end wall to constitute an ornamental band, said projecting portion being rolled inwardly to form a 35 bead.

3. In a paper box, the combination with a laminated side wall having a thin inner sheet of metal incorporated therein with its end edge extended beyond the paper to constitute an exposed band of metal, of a separate end wall supported by such extended portion.

4. In a paper box, the combination with a laminated side wall having a thin inner sheet of metal incorporated therein with its end edge extended beyond the paper to constitute an exposed band of metal, and rolled inwardly to form a bead, of a separate end wall supported on said bead.

5. A paper box having laminated side walls of paper and metal sheets the metal being innermost, and a paper bottom supported by an extension of the metal sheet upon which extension the box is adapted to 55 rest.

GEORGE S. BARTOLD.
